COLLAR CREEASING AND IRONING APPARATUS

John W. Creswell, Shelby, N. C., assignor of one-fourth to Mason E. Peters, Shelby, N. C.

Application November 28, 1938, Serial No. 242,842

6 Claims. (Cl. 223—52.6)

This invention relates to a collar and neck band shaper and finisher and the purpose is to expedite the ironing operation on shirt collars. Heretofore shirt collars have been ironed and finished by manual means and in most cases, no means have been provided for properly creasing the collar so as to provide ample room for the necktie to be slid therein. Instead the collar has been creased very sharply and the fabric is thus damaged along the bend line due to this acute bending, especially when the collar is starched. Also there has been much trouble in obtaining a uniform ironing operation by manual means, because the crease would not be properly positioned each time.

It is, therefore, an object of this invention to provide a shaping and finishing apparatus for setting a crease in a collar which crease is of such shape and size as to permit free movement of a necktie therein. This result is obtained by providing a suitable mandrel of such shape and thickness which may be used to crease the collar thereover, thereby allowing the inner fold of the collar to be disposed on one side of the mandrel and the outer fold on the other side. When in this position, a shaping apparatus or heated form is lowered onto the mandrel to set the crease in the collar.

It is a further object of this invention to provide an apparatus for shaping and finishing collars comprising a mandrel for supporting a collar, a pivoted steam chest having a groove in its lower side for creasing the collar over the mandrel and means for resiliently supporting the mandrel, both vertically and laterally, whereby the mandrel will adjust itself to the groove in the steam chest when said chest is lowered thereon.

It is a still further object of this invention to provide an apparatus of the class described comprising a mandrel over which a creased collar of a collar attached shirt is placed so that one fold of the collar will be disposed on one side of the mandrel and the other fold of the collar will be disposed on the other side, with means for initially engaging the outside fold of the collar upon the lowering of a heated form, and a resilient means for simultaneously contacting the interior of the shirt below the collar to thereby hold the collar in position while the form is being lowered. By providing means for contacting both sides of the creased fabric while the form is being lowered, it is seen that a more uniform operation is obtained, because there is less likelihood of the collar slipping relative to the mandrel. This resilient means for contacting the interior

of the shirt, also serves to hold the collar in contact with the mandrel while the heated form is being raised. Therefore, if a bond between the form and the collar is formed while the crease is being set, the resilient means will serve to hold the collar on the mandrel as the form is raised and as the bond is broken.

Some of the objects of this invention having been stated, other objects will appear as the description proceeds when taken in connection with the accompanying drawings, in which—

Figure 1 is an elevation of a collar and neck band shaper and finisher made in accordance with the invention;

Figure 2 is an elevation looking at the right-hand side of Figure 1;

Figure 3 is an enlarged vertical sectional view taken along the line 3—3 in Figure 1;

Figure 4 is a sectional plan view through the steam chest or form and taken along the line 4—4 in Fig. 2;

Figure 5 is a sectional plan view taken along the line 5—5 in Figure 2, but omitting the steam chest or form;

Figure 6 is a sectional view similar to Figure 3, but showing the steam chest in an elevated position prior to its being lowered upon the mandrel;

Figure 7 is a view similar to Figure 6, but showing the mandrel in a lower position, at which time the opposed exterior surfaces of the creased collar are being contacted;

Figure 8 is an exploded isometric view of a resilient supporting means for the mandrel;

Figures 9 is a developed view of a collar, shown attached to a portion of the shirt;

Figure 10 is a sectional view similar to the central portion of Figure 3, but showing a slightly modified form of the invention in which a greater portion of the neck band of the collar is finished.

Referring more particularly to the drawings, the numeral 10 denotes a suitable U-shaped base portion which has secured to its upper end suitable brackets 11. Each of the brackets 11 has a hollow stud screw 12 rotatably mounted therein, the proximate ends of the stud screws being threaded secured in an arm 14 (Figures 2, 3 and 4).

Leading into one of the stud screws 12 is an inlet steam pipe 15, said pipe being secured with the screw by means of a packing nut 16. Likewise an outlet steam pipe 17 is held in position by means of a similar packing nut 18. It will be noted that the arm 14 has hollow bores 19 and 20 therein. The left-hand ends of these bores communicate with a space 21 in a cap 22. Steam is allowed to flow from pipe 15 into bore 19 thence

5

35

40

50

55

into space 21, after which it enters bore 20 and passes out through pipe 17.

The lower side of cap member 22 has a circular groove 25 therein which is adapted to fit 5 upon the top edge of a circular mandrel 26. Mandrel 26 is supported by means of suitable resilient leaf spring members 27 such as shown in Figures 1, 5 and 8. It will be noted that the spring members 27 have holes 29 and 30, in the ends thereof 10 which are slightly larger than bolts 31 and 32 which penetrate them. The bolts 31 and 32 are also adapted to threadably penetrate hole 26a in mandrel 26 and hole 34a in supporting block 34 respectively, to provide resilient connecting members between the mandrel 26 and the framework 10.

The rear side of the mandrel 26 is supported in a similar member by a resilient leaf spring member 35 (Figures 4 and 5). This member is 20 secured to a lug 36 on the mandrel 26 by any suitable means such as a pin 37, and the other end of the spring member 35 is secured to a block 38 by any suitable means such as screws 39. The block 38 has a bore therethrough which is slidably penetrated by a bolt 40. Bolt 40 has a nut 41 on one end thereof and a fixed collar 42 integral with its intermediate portion. Between the collar 42 and the block 38 is a compression spring 43. The right-hand portion of the bolt 25 30 (see Figure 3) penetrates a suitable slot 45 in the upper portion of the supporting framework 10 and a suitable washer 46 and nut 47 are provided for holding the bolt in adjusted position.

The purpose in boring the holes 29 and 30 35 somewhat larger than the screw 31 and 32, as shown in Figure 8, is to allow a certain amount of vertical as well as lateral movement of the mandrel 26 so that this member may adjust itself to the groove 25 in the lower side of the cap member 22. The block 38 is slidably mounted upon the bolt 40 in order to likewise allow lateral movement of the resilient supporting member 35. It is seen that the mandrel is loosely supported at three points in a resilient manner, 40 therefore the groove 25 in the cap member 26 45 will always move the mandrel to its proper position when the cap member is lowered to the position shown in Figure 3. The slot 45 is provided so that the vertical position of the bolt 40 may be varied and thereby the tilt of the mandrel determined.

When it is desired to place a crease in a 50 collar 50 (Figure 9), the collar is damped along crease lines 51. Then it is folded upon this crease line with the outer fold of the collar disposed on the exterior of the mandrel as shown in Figures 3, 6 and 7 and the inner fold of the collar is disposed on the interior thereof. A shirt 52 to which the collar is shown attached, is allowed to fall downwardly within the U-shaped member 10 and be partially supported by platform 53. With the collar in this position, the heated cap 55 50 is lowered until the groove 25 will be properly seated upon the creased collar and press it firmly upon the mandrel 26.

Prior to performing the crease setting operation, however, the collar 50 is laid with the flattened or developed position upon a suitable table 58, which table is hingedly secured as at 59 to the upper portion of the supporting framework 10. This table is held in horizontal position by means of a suitable brace 60, the upper end of which is hingedly secured as at 61 to the lower side of the platform 58 and the lower end of 60 70 said brace is adapted to rest in a suitable notch

62 in the framework. It is while the collar is disposed upon this table with the finish side up that a suitable moistening substance is applied. This moistening substance is carried by a suitable container 63 which is likewise attached to the upper side of the framework 10.

In order to determine the amount of weight applied by the cap member 22 and to the creased collar 50, a suitable adjustable weight member 68 is provided, said weight member being threadably secured around a rod 69 and this rod is supported by post members 70 and 71 which rest upon the cap member 22 and arm 14, respectively. The threaded rod 69 has a wheel 72 fixed on one end thereof which may be turned when it is desired to vary the position of the weight 68. This weight has a notch 73 in its lower side, which notch is adapted to straddle horizontally disposed member 14 and post 71. The purpose of notch 73 and member 14 is to prevent rotative movement of the weight 68. It is evident by observing Figure 3 that the nearer the weight 68 is disposed to post 70, the greater amount of weight will be applied to the cap member 22.

The cap 22 has a suitable handle 77 which is 25 grasped by the operator when the cap member is being lowered from dotted line position as shown in Figure 2 to bold line position, or vice versa.

It is very desirable to have means for initially 30 engaging the interior of the shirt immediately below the neck band of the creased collar simultaneously with the engagement of the down-turned portion of the collar by rim 22a of the cap member 22. Unless some means is provided for 35 applying a force to the interior of the shirt below the creased collar at the same time a force is applied to the outside there is a danger of the collar slipping upon the mandrel, before the cap reaches its lowermost position. Therefore, a suitable forked member 80 has been provided which is slidably mounted upon the lower end 81a of rod 81. The upper end of rod 81 is pivoted as at 82 to the lower side of cap member 22. When the cap is in a raised position the intermediate portion of the rod 81 is supported by U-shaped loop 83 which also extends from the lower side of the cap member 22. A spring 84 is disposed around the rod 81 and between collar 81b and the fork member 80. The spring normally forces 40 the prong of the fork member to extended position as shown in Figure 6 when the cap is in a raised position. As the cap is lowered, the ends 80a of the prongs contact the shirt 52 directly below the collar as shown in Figure 7. Simultaneously with the contacting of the shirt 52 by the ends 80a, the lip 22a of cap member 22 contacts the portion of the collar disposed on the outside of the mandrel 26. It is seen that by providing this means for simultaneously contacting the shirt on opposed sides of the mandrel that the collar is held in its proper position prior to the cap member reaching its lowermost position. It should also be noted that as the cap member 22 is lowered from the position shown in Figure 7 to the lowermost position as shown in Figure 3, the fork member 80 gives way, that is slides, upon squared portions 81a, thereby compressing the spring 84. This will allow the overall length of members 80 and 81 to be gradually 70 shortened and also will allow the angle between the lower surface of the head member 22 and the rod 81 to decrease as the head or cap member 22 is lowered.

The groove 25 is so shaped that the interior 75

fold of the collar after being placed upon the mandrel will be properly compressed, ironed and finished. Also the exterior of the collar will be folded down to the proper position. With this 5 groove properly seated upon the collar and the mandrel, the heat therein will set the crease and after the proper setting has been effected, the head portion 22 is rotated to dotted line position as shown in Figure 2 so that the collar and shirt 10 may be removed. As the head portion is being rotated upwardly, the forked member remains in contact with the shirt to hold it on the mandrel while the bond between the collar and groove 25 is being broken.

15 Special attention is called to the size and shape of groove 25. The diameter of this groove is slightly greater than the diameter of the mandrel 26. Also, the lower portion of the inner wall of this groove is rounded as at 25a. Consequently 20 the rounded portion 25a will engage the top of the collar on the mandrel 26 and as the groove approaches its lowermost position, the mandrel is expanded. This expansion causes the inner 25 wall of the groove 25 to snugly press against the neckband of the collar 50 and finish it while the crease is being set.

Figure 10 shows a slightly modified form of the invention in which the member 14 has a head 95 secured thereto, said head having a groove 96 therein which merges into inner sidewall 97. The lower portion of this sidewall merges with a rounded portion 98. In this form, the inner sidewall is made of greater width so as to iron and finish a greater surface of the neckband of collar 50. The rounded portion 98 expands the mandrel in the same manner as in the preceding form.

It is thus seen that by providing this type of apparatus that the finishing of a collar can be 40 restricted to a minimum number of operations. It is not necessary to perform any manual operations except to moisten the collar along the crease lines 51 prior to inserting it over the mandrel. With a collar thus finished, and creased, 45 ample room is provided for free movement of the necktie therein.

In the drawings and specification, there has been set forth a preferred embodiment of the 50 invention, and although specific terms are employed, they are used in a generic and descriptive sense only, and not for purposes of limitation, the scope of the invention being set forth in the appended claims.

55 I claim:

1. In a machine for shaping collars on men's shirts comprising a frame, a curved member mounted in the frame and over which the collar is placed to support the collar with its inner 60 fold against the inner face of the curved member and its outer fold being disposed against the outer surface of the curved member, a heated member mounted in the frame for movement into engagement with the collar on the curved member and having a groove therein conformable to the shape of the curved member for fitting over the curved member and pressing the inner and outer folds of the collar and the junction point of the inner and outer folds of the collar against the curved member for forming a crease at the junction point of the inner and outer folds of the collar, a pair of spaced projections rising from the top of the heated member and having a threaded rod turnably mounted therein, said rod extending longitudinally of the heated member, 65 a weight threadably mounted on said rod, and

means for preventing turning movement of said weight when the rod is turned to adjust the position of the weight longitudinally of the heated member.

2. Apparatus for shaping collars on collar attached shirts, comprising a frame, an arcuate member mounted in the frame and over which the inner and outer folds of the collar are adapted to be placed, and a heated member having an arcuate groove therein and mounted in the frame for movement relative to the arcuate member for fitting over the upper edge of the collar and pressing it against the arcuate member, and means pivotally mounted on the heated member for engaging the shirt below the junction point between the shirt and the collar and before the heated member engages the collar, as the heated member is moved into engagement with the collar for holding the shirt and its collar in position to be engaged by the heated member. 20

3. In a machine for shaping collars on men's shirts comprising a frame, a curved member mounted in the frame and over which the collar is placed to support the collar with its inner fold against the inner face of the curved member and its outer fold being disposed against the outer surface of the curved member, a heated member mounted in the frame for movement into engagement with the collar on the curved member and having a groove therein conformable to the shape 30 of the curved member for fitting over the curved member and pressing the inner and outer folds of the collar and the junction point of the inner and outer folds of the collar against the curved member for forming a crease at the junction point of the inner and outer folds of the collar, and means pivotally mounted on the heated member for engaging the shirt below the collar before the heated member engages the collar as the heated member is moved into engagement with the collar for holding the shirt and its collar in position to be engaged by the heated member, a pair of spaced projections rising from the top of the heated member and having a threaded rod turnably mounted therein, said rod extending 35 longitudinally of the heated member, a weight threadably mounted on said rod, and means for preventing turning movement of said weight when the rod is turned to adjust the position of the weight longitudinally of the heated member. 50

4. Apparatus for shaping a moistened turn down collar on a collar attached shirt, comprising a frame, a curved member mounted in the frame and over which the inner and outer folds of the collar are adapted to be placed whereby the collar will be supported at the fold line between its inner and outer folds, a heated member pivoted on the frame for swinging movement and having an arcuate groove in its lower face conformable to the shape of the curved collar supporting 60 member and movable into engagement with the fold line and adjacent portions of the inner and outer folds for applying pressure and heat to the collar to set the fold line in the collar and to shape the portions of the inner and outer folds 65 of the collar which are adjacent to the fold line, and means pivotally mounted at one end thereof on the heated member for engaging the shirt with its other end before the heated member is moved into engagement with the collar for holding the 70 shirt and its collar in position to be engaged by the heated member, a pair of spaced projections rising from the top of the heated member and having a threaded rod turnably mounted therein, said rod extending longitudinally of the heated 75

member, a weight threadably mounted on said rod, and means for preventing turning movement of said weight when the rod is turned to adjust the position of the weight longitudinally of the heated member.

5. In a machine for shaping collars on men's shirts comprising a frame, a curved member mounted in the frame and over which the collar is placed to support the collar with its inner fold 10 against the inner face of the curved member and its outer fold being disposed against the outer surface of the curved member, a heated member mounted in the frame for movement into engagement with the collar on the curved member and 15 having a groove therein conformable to the shape of the curved member for fitting over the curved member and pressing the inner and outer folds of the collar and the junction point of the inner and outer folds of the collar against the curved member for forming a crease at the junction point 20 of the inner and outer folds of the collar, and means for resiliently supporting the curved member, a pair of spaced projections rising from the top of the heated member and having a 25 threaded rod turnably mounted therein, said rod extending longitudinally of the heated member, a weight threadably mounted on said rod, and means for preventing turning movement of said weight when the rod is turned to adjust the position 30 of the weight longitudinally of the heated member.

6. Apparatus for shaping a moistened turn down collar on a collar attached shirt, comprising a frame, a curved member mounted in the frame and over which the inner and outer folds of the collar are adapted to be placed whereby 5 the collar will be supported at the fold line between its inner and outer folds, a heated member pivoted on the frame for swinging movement and having an arcuate groove in its lower face conformable to the shape of the curved collar 10 supporting member and movable into engagement with the fold line and adjacent portions of the inner and outer folds for applying pressure and heat to the collar to set the fold line in the collar and to shape the portions of the inner and outer 15 folds of the collar which are adjacent to the fold line, and means for resiliently supporting the curved member at a plurality of points so that the fold line of the collar will at all points be engaged by the groove in the heated member, a 20 pair of spaced projections rising from the top of the heated member and having a threaded rod turnably mounted therein, said rod extending longitudinally of the heated member, a weight threadably mounted on said rod, and means for 25 preventing turning movement of said weight when the rod is turned to adjust the position of the weight longitudinally of the heated member.

JOHN W. CRESWELL. 30
